PALLET JEWEL SETTER

John Vinardi, Rosedale, Ind.

Application August 18, 1939, Serial No. 290,981

10 Claims. (Cl. 33--184)

This invention relates to a pallet jewel setter, the general object of the invention being to provide a device whereby the watchmaker or watch-repairer can, by the use of a three point system, determine any escapement error in the watch; i. e., any disalignment of the escapement wheel pivot hole center, the pallet arbor pivot hole center and the balance jewel center, and by which distortions or bends or dents in the escapement lever of the watch can be detected and also the degree of such disalignment or distortion can be ascertained so that a corresponding allowance may be made in setting the pallet jewels, thereby setting the pallet jewels on either side of the line of center so as to compensate for any such disalignment or distortion.

A further object of the invention is to enable a watch-maker or watch-repairer to set varying sizes of pallet jewels having either straight line escapements or right angle escapements with the one device and specifically to enable the setting of pallet jewels in watches of the type varying from the small modern bracelet straight line lever watch escapement to the 18 size detached lever type, and further to enable, by use of the same device, the setting of pallet jewels for right angle escapements consisting of either double roller or single roller escapements.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a top plan view of the invention.
Figure 2 is a view looking toward one side thereof.

Figure 3 is a view looking toward the other side.
Figure 4 is a front view.

Figure 5 is a fragmentary top plan view with parts in section.

Figure 6 is a fragmentary side view with parts in section and parts omitted.

Figure 7 is a fragmentary sectional view of the turret assembly.

Figure 8 is a horizontal sectional view through the turret assembly and showing the worm means for rotating the turret and the means for locking the turret against movement.

Figure 9 is a top plan view of the index lever.

Figure 10 is a section on the line 10--10 of Figure 3.

In these drawings the numeral 19 indicates an angle-shaped base or supporting member having a forked bracket 19' adjustably connected for rotary movement to its upper end by a screw 19" and a base plate 31 is attached to the outer end of the prongs of the bracket by the screws 1' engaging threaded holes in the base plate. This plate is preferably of the shape shown in Figure 1 with a short and straight side edge at each of its four corners, three of these side edges having slots 36 therein while the fourth has the graduating marks 38 thereon. A bridge member 2 extends upwardly from the base plate and this bridge member is formed of the long part 2' and the short part 2", these parts being horizontally arranged and each part is formed with a depending portion having a right angle foot part 3' and these parts 3' are connected with the base plate 20 by screws 3 which pass in threaded holes in the base plate 31. A substantially U-shaped bridge member 4 is movably supported by the bridge member 2 by having the upper horizontal part of the bridge member 4 slidably arranged between the parts 2' and 2" of the bridge member 2. The inner end of this part of the bridge member 4 extends beyond the inner end of the short part 2' of the bridge member 2 but the inner end of the long part 2' of the bridge member 2 projects beyond the inner end of the upper portion of the bridge member 4. The bight of the bridge member 4 extends downwardly through one of the slots 36 in the base plate with its other limb located under the base plate and paralleling the 35 same. The two parts 2' and 2" of the bridge member 2 are fastened together by screws or other fastening means as shown and they form a guideway for the upper limb of the bridge member 4. An opening 4' is formed in said upper limb 40 of the bridge member 4 and a screw 25' has its ends held against movement in the end walls of this opening and a nut 25 is threaded on the screw and passes through slots in the members 2' and 2" of the bridge member 2 so that by rotating 45 this nut in one direction or the other the bridge member 4 is moved inwardly or outwardly according to the direction of turning movement of the nut. The bridge member 4 is held in adjusted position by a set screw 4" and a friction spring 50 50 is placed in a groove in the upper limb of the bridge member 4 and bears against a part of the bridge member 2.

The ends of the upper and lower limbs of the bridge member 4 are provided with the vertical- 55

- ly arranged bearings 29 and 32 for the depthing points 5 and 6 and the long member 2' of the bridge member 2 is provided with vertically arranged bearings 28 for the depthing point 7.
- 5 Locking means 9, 11 and 12 are provided for holding the points 5, 7 and 6 in adjusted position and each of these means includes a nut located in a slot in a bridge member and threaded on a screw shaft arranged in a plain bore in the bridge member and held against rotary movement so that when the nut is turned in one direction or the other the screw shaft is moved longitudinally into engagement with a point or out of engagement therewith. A small plate 9' bears against a flattened part of each screw shaft to hold the screw shaft against turning movement while permitting it to slide, each plate being held in place by a pair of screws as shown. Depthing points of different sizes can be used in the device.
- 10 An index lever 13 has its inner end connected by screws or other fastening means to the tubular reduced and circular upper end of a member 30, said reduced upper end of the member 30 being rotatably arranged in a hole in the base plate 31, as shown in Figure 6 and a depthing point 8 passes through a vertically arranged bore in the member 30 and is held in adjusting position by the locking means 10 which are similar to those before described and include a nut on a threaded screw shaft supported for longitudinal movement in the member 30. Each of these depthing points 5, 6, 7 and 8 has one end pointed and the other end is cupped and has a hole adjacent the cup as is usual in devices of this nature.
- 15 The lever 13 has its inner portion of considerable width and this part operates in an opening in the base plate 31 and this part has a slot therein and a groove, said groove receiving for sliding movement the index plate 14 which also has a slot therein registering with the slot of the lever 13 and it also has a pair of holes 15 therein and a center line 28' as shown in Figure 9. The outer portion of the lever 13 passes under a portion of the base plate 31 with the outer end 20 of the lever 13 bent upwardly and then inwardly into hook shape so that this hook portion will pass over that part of the plate 31 which carries the graduation marks 38, as shown in Figures 1 and 2 with the end of the upper portion of the hook part pointed to act as a marker on the graduations. A small spring 13' is carried by the hooked part of the lever 13 and frictionally engages an under part of the plate 1 to yieldingly hold the lever in adjusted position.
- 25 A carriage 16 is slidably arranged on the lever 13 and is held in adjusted position by a bolt 26 which passes through the slots in the plate 14 and in the lever 13 and by moving this carriage, after loosening the bolt, to a certain extent and then continuing this movement the plate 14 is moved in the slot of the lever 13 and the parts are held in adjusted position by tightening the bolt 26. The carriage has pivoted thereto the pair of substantially L-shaped levers 17 and each lever has an upstanding part at its outer end for engaging a groove in a small wheel 51, these wheels being carried by threaded stems extending outwardly in opposite directions from an upright 30 52 on the rear of the carriage. Thus by turning one of these wheels 51 it is caused to move inwardly or outwardly on the threaded stem and thus the wheel causes rocking movement of a lever 17. These levers 17 act to hold a watch lever on the lever 13 and by adjusting the car-

riage on the lever 13 various sizes of watch levers can be held on said lever 13.

A turret supporting plate 55 has a part extending under the base plate 31 and said plate 55 is adjustably held to the base plate by a screw 35 engaging a threaded hole 33 and a pin 56' on the plate 55 engaging another one of the holes 33. This turret supporting plate 55 may be connected with that side of the base plate to which it is connected as shown in Figure 1 or it may be connected to the opposite side if desired. A plate 34 having a circular opening therein and a split leading from the opening through a side edge of the plate is fastened by screws or the like to the outer part of the plate 55 and a shaft 22 extends into a recess in the plate 34 and is rotatably supported by the plate 34 and said shaft has a worm 39 thereon meshing with the worm gear 23 located in the circular recess and connected with the lower end of a turret 56 which has a flanged lower end located in the circular recess. Thus by turning the shaft 22 by its knurled head the turret can be partly rotated. The slit or split in the plate 34 makes a part thereof slightly flexible and the portions of the plate through which the split passes having threaded holes therein for receiving the threaded part of the turn screw 24 so that by turning the screw in one direction the slotted parts are moved toward each other so as to clamp the worm 39 and the gear 23 together to lock the parts against rotary movement. Of course, by turning the screw 24 in the opposite direction the parts will be loosened so that the turret will be turned when the shaft 22 is turned. An elongated tubular member 57 passes vertically through the turret 56 and has a bore passing longitudinally therethrough, the lower part of which is screw-threaded and a threaded shaft 58 passes through the bore with its upper end enlarged and unthreaded and provided with a knurled head 21. Thus by turning the shaft 58 by the head 21 the engagement of the threaded part with the member 57 will cause longitudinal movement of the member 57 as this member is held against rotary movement. The shaft 58 is held against longitudinal movement by having a head 59 on its lower end rotatably arranged in a recess in the plate 55 but held against vertical movement in said recess.

A portion of the turret is cut away at one side thereof to expose a portion of the member 57 and a horizontally arranged plate 40 is fastened to this exposed part of the member 57 so that the plate 40 is moved vertically when the member 57 is moved vertically by turning the shaft 58.

A pointer bar 20 passes through a passage in the plate 40 and said bar has a threaded portion 20' which is engaged by a nut 37 passing through a slot in the plate 40 so that by turning this nut 37 the bar 20 is moved longitudinally in the plate 40. The bar 20 is locked in adjusted position by the locking means 60, see Figure 7, said means including a nut passing through a slot in the plate 40 and a threaded shaft longitudinally movable in the plate 40 and moved by turning movement of the nut 60, this locking means being similar to that before described and used for holding the depthing points in adjusted position. This rod or bar 20 has its free end bent downwardly and pointed as shown in dotted lines in Figure 4.

As will be seen by turning the shaft 22 the turret with the plate 40 can be partly rotated and by turning the shaft 58 the plate 40 can be

raised and lowered and by turning the nut 37 after loosening the locking means 60 the rod 20 can be projected or retracted.

Points 5 and 7 are used to determine the depthing of the escapement wheel pivot and the pallet arbor pivot, the point 5 being adjusted toward or away from the point 7 to center the points over the escapement wheel pivot and pallet arbor pivot by moving the bridge member 4 by means of the nut 25 and screw 25'. The depthings can be taken from the lower or upper watch plate. After the depthings are obtained the points 5 and 7 are reversed to bring the ends containing the small cavities lowermost and the points 5 and 6 are adjusted vertically to hold the escapement wheel pivot and the points 7 and 8 are adjusted to engage the pivot of the watch lever. The levers 17 are adjusted by turning the wheels 51 to cause said levers to hold the watch lever on the line of center 28' of lever 13 of the device. In a single roller escapement, the guard pin of the watch lever is dropped into the hole 15 in the index plate 14 to align the watch lever with the line of the center 28'. The pointer bar 20 is adjusted to determine the depthing of the balance staff pivot center of the watch from the lower plate of the watch. Then after the watch plate is removed the pointer bar is lowered on the line of center 28' on plate 14 to indicate whether or not the balance staff pivot center is on the line of center 28'. If it is not then the lever 13 is adjusted and the graduations 38 will indicate the degree the pivot hole or bearing is off-center as indicated by the depending and pointed lower end of the bar 20 on the plate 14. This will enable the pallet jewel or jewels to be set to compensate for the amount the pivot center is off the line of center.

Also by placing the watch lever on line of center 28' on plate 14 and then operating the index lever 13 it can be determined whether the watch lever is distorted, dented or bent. Lever 13 is moved until the escapement wheel tooth drops from the impulse face of the pallet jewel upon the receiving pallet jewel and cognizance taken of the degree as shown by the graduations 38 at which such dropping occurs. The lever 13 is then moved in the opposite direction until the escapement wheel tooth drops from the discharging pallet jewel and the degree of such dropping is also taken cognizance of as shown on the graduations 38. The difference, if any, between the two noted degrees of each dropping is the amount of distortion, dent or bent in the watch lever and appropriate allowance may be made for such differences in setting the jewels. As before stated the watch lever is held in position on the line of center 28' by the points 7 and 8 and the levers 17 and by adjusting the carriage 16 which carries the levers 17 said lever can be made to hold various sizes of watch levers. These levers 17 are independently adjustable and are thereby enabled to be adjusted to hold the watch lever firmly and accurately on the line of center 28' throughout the setting of the pallet jewels.

By removing screws 3 the entire bridge assembly including the bridge members 2 and 4 and the depthing points 5, 6 and 7 can be placed at a right angle by placing the screws 3 in other holes 33. Then the device can be used for setting right angle escapement pallet jewels. Turret assembly can also be moved to opposite sides of the base plate as before stated. The invention also contemplates the use of a depthor rotor

18 when desired. This member 18 is attached to the lower end of the point 5 and a knurled head 5' is attached to the upper end of this member 5 so that it can be readily turned. This member 18 is formed with the lips 27, as shown in Figure 5. This member 18 is used when only slight adjustment of the escapement lock of the pallet jewels are desired without taking depthings from the watch plate as above described. By holding the watch lever in depthing points 10 7 and 8 and setting the rotor lips 27 so as to bite the pallet jewel which is being set and by setting the index lever 13 on the desired degree there is obtained an accurate adjustment between the lock of the escapement wheel tooth and the 15 pallet jewel or jewels. This member 18 is attached to the point 5 by a set screw or the like and it has a hole therein for receiving the upper end of the point 6 as shown in Figure 6.

In starting to use the device the carriage 16 20 is removed by taking out the carriage bolt 26 and bar 20 is swung to the right in Figure 1. Point 5 with rotor 18 is removed and a point similar to that shown at 7 is substituted for point 5, with the pointed end lowermost. The watch plate is then placed on lever 13 and the point which has been substituted for point 5 is centered on the escape wheel pivot hole center of this watch plate after which the point is locked in adjusted position by the locking means 11 and point 7 is centered to pallet arbor center. Then bar 20 is swung to a position where its depending end will be over the center of the balance wheel pivot hole or over the jewel bearing if one is placed in said hole. After the depthing is taken bar or rod 20 is raised by turning shaft 58 and the watch plate removed and then the bar or rod 20 is lowered to place its depending end adjacent index plate 14 and then lever 13 is adjusted to place the line 28' under the depending end of the bar or rod 20, if said line is not already under said depending end. The marker on the outer end of lever 13 will indicate on the scale 38 the number of degrees the depending end of bar 20 is on either side of the line of 45 center 28'.

After the readings are taken the points 5, 7, 6 and 8 are reversed to bring their pivot receiving ends into operative position and the watch lever put in place with the points 7 and 8 holding the pallet arbor of the lever and the points 5 and 6 holding the escapement wheel. Then carriage 16 is replaced and the wheels 51 are turned to cause the lever 17 to grip the watch lever with the parts on the line of center 28'. 55 If the watch lever is for a single roller escapement, the guard pin of the lever is inserted in hole 15, but if the lever is for a double roller escapement then it is not necessary to use the guard pin in the hole 15.

When the parts have been adjusted to have the escapement wheel and pallet arbor, with the watch lever held on line of center 28' and the parts held securely in this position, then the 65 watchmaker or repairman can set the pallet jewel, allowing the necessary lock and drop.

It is thought from the foregoing description that the advantages and novel features of the invention will be readily apparent.

It is to be understood that changes may be made in the construction and in the combination and arrangement of the several parts provided that such changes fall within the scope of the appended claims.

Having described the invention, what is claimed as new is:

1. A watchmaker's tool comprising a base member, a base plate supported by said member, a stationary bridge member supported by the base plate and extending horizontally over the same, vertically arranged bearing parts at the inner end of said horizontal part for receiving a depthing point, a substantially U-shaped bridge member including upper and lower limbs, means for slidably supporting the U-shaped bridge member from the stationary bridge member, one of the limbs of the U-shaped member being located above the base plate and parallel with the horizontal part of the stationary bridge member and the other limb of the U-shaped bridge member being located below the base plate, vertically arranged bearing parts at the ends of the limb being in vertical alignment with the bearing parts of one limb being in vertical alignment with the bearing parts of the other limb, depthing points carried by said parts of both limbs, means for holding the three depthing points in adjusted position, means for adjusting the U-shaped bridge member horizontally in the stationary bridge member, a fourth depthing point bearing member depending from the base plate and rotatably supported thereby and having a depthing point receiving bearing therein which is in alignment with the bearing part of the stationary bridge member, a horizontally arranged lever connected with the upper end of the depending rotary member, said base plate having graduations thereon and the lever having a pointer associated with the graduations, index means carried by the lever, a turret rotatably supported from the base plate, means for rotating the turret, a carrier carried by the turret, means for raising and lowering the carrier, a pointer bar supported for longitudinal movement in the carrier, means for adjusting the bar longitudinally in the carrier, said bar having its free end provided with a depending point for cooperating with the index means of the lever.
2. A watchmaker's tool comprising a supporting member including a base plate, a stationary bridge member extending over the plate, means for holding a depthing point by the bridge member, a U-shaped bridge member supported for horizontal movement on the supporting plate and having a part above the plate and a part below the plate, each part having means for holding a depthing point, a lever, a member attached to the inner end of the lever and depending therefrom and rotatably supported in the plate, means for holding a fourth depthing point in said member, index means adjustably carried by the lever, graduations on the base plate and a pointer on the lever cooperating with the graduations, a carrier, means for partly rotating the same about a vertical pivot and for raising and lowering the carrier, a pointer bar horizontally arranged in the carrier and supported for sliding movement, means for adjusting the bar, said bar having a depending free end for cooperating with the index means of the lever.
3. A watchmaker's tool comprising a supporting member including a base plate, a stationary bridge member extending over the plate, means for holding a depthing point by the bridge member, a U-shaped bridge member supported for horizontal movement on the supporting plate and having a part above the plate and a part below the plate, each part having means for holding a depthing point, a lever, a member attached to the inner end of the lever and depending therefrom and rotatably supported in the plate, means for supporting upper and lower depthing points from said plate, means for supporting another pair of upper and lower depthing points from said plate, means for adjusting one pair toward and away from the other pair, a carrier member supported from the plate, means for adjusting said carrier member about a vertical pivot, means for raising and lowering the carrier member, a pointer bar slidably arranged in the carrier and means for moving the bar longitudinally in the carrier, a lever having its pivotal point in vertical alignment with the stationary pair of depthing points, means for indicating the degree of movement of the lever and index means carried by the lever and associated with the free end of the sliding rod.
4. A watchmaker's tool comprising a supporting member including a base plate, a stationary bridge member extending over the plate, means for holding a depthing point by the bridge member, a U-shaped bridge member supported for horizontal movement on the supporting plate and having a part above the plate and a part below the plate, each part having means for holding a depthing point, a lever, a member attached to the inner end of the lever and depending therefrom and rotatably supported in the plate, means for holding a fourth depthing point in said member, index means adjustably carried by the lever, graduations on the base plate and a pointer on the lever cooperating with the graduations, a carrier, means for partly rotating the same about a vertical pivot and for raising and lowering the carrier, a pointer bar horizontally arranged in the carrier and supported for sliding movement, means for adjusting the bar, said bar having a depending free end for cooperating with the index means of the lever, said index means including a center indicating line and a hole.
5. In a watchmaker's tool including a supporting plate, means for supporting upper and lower depthing points from said plate, means for supporting another pair of upper and lower depthing points from said plate, means for adjusting one pair toward and away from the other pair, a carrier member supported from the plate, means for adjusting said carrier member about a vertical pivot, means for raising and lowering the carrier, a pointer bar slidably arranged in the carrier and means for moving the bar longitudinally in the carrier.
6. In a watchmaker's tool including a supporting plate, means for supporting upper and lower depthing points from said plate, means for supporting another pair of upper and lower depthing points from said plate, means for adjusting one pair toward and away from the other pair, a carrier member supported from the plate, means for adjusting said carrier member about a vertical pivot, means for raising and lowering the carrier member, a pointer bar slidably arranged in the carrier and means for moving the bar longitudinally in the carrier, a lever having its pivotal point in vertical alignment with the stationary pair of depthing points, means for indicating the degree of movement of the lever and index means carried by the lever and associated with the free end of the sliding rod.
7. In a watchmaker's tool including a supporting plate, means for supporting upper and lower depthing points from said plate, means for supporting another pair of upper and lower depthing points from said plate, means for adjusting one pair toward and away from the other

pair, a carrier member supported from the plate, means for adjusting said carrier member about a vertical pivot, means for raising and lowering the carrier member, a pointer bar slidably arranged in the carrier and means for moving the bar longitudinally in the carrier, a depthor rotor detachably connected with the pair of adjustable depthing points at the adjacent ends of said points and lips carried by the rotor.

8. A watchmaker's tool comprising a base plate, upper and lower depthing points supporting means carried by the plate, a member supported for horizontal adjustment from the plate, upper and lower depthing points supporting means carried by said member, the last-mentioned depthing points depthing the escapement wheel center and the first pair the pallet arbor center, a horizontal bar having a depending pointed end for determining the balance staff center, means for moving the bar longitudinally and for partly rotating the bar about a vertical pivot.

9. A watchmaker's tool comprising a base plate, upper and lower depthing points supporting means carried by the plate, a member supported for horizontal adjustment from the plate, upper and lower depthing points supporting means carried by said member, the last-mentioned depthing points depthing the escapement wheel center and the first pair the pallet arbor

center, means for moving the bar longitudinally and for partly rotating the bar about a vertical pivot.

center, a horizontal bar having a depending pointed end for determining the balance staff center, means for moving the bar longitudinally and for partly rotating the bar about a vertical pivot, a lever pivoted to the supporting plate and having index means thereon, means for indicating the amount of swinging movement of the lever, said index means being associated with the pointed end of the bar.

10. A watchmaker's tool comprising a base plate, upper and lower depthing points supporting means carried by the plate, a member supported for horizontal adjustment from the plate, upper and lower depthing points supporting means carried by said member, the last-mentioned depthing points depthing the escapement wheel center and the first pair the pallet arbor center, a horizontal bar having a depending pointed end for determining the balance staff center, means for moving the bar longitudinally and for partly rotating the bar about a vertical pivot, a lever pivoted to the supporting plate and having index means thereon, means for indicating the amount of swinging movement of the lever, said index means being associated with the pointed end of the bar, and means for adjusting the bar carrying means and the depthing points carrying means to different parts of the supporting plate.

JOHN VINARDI. 30
